Primary Examiner—Caron D. Veynar*Assistant Examiner*—Abraham Bahta(74) *Attorney, Agent, or Firm*—McDonald Hopkins LLC; Robert H. Earp, III(57) **CLAIM**

The ornamental design for a display unit with two pockets, as shown and described.

DESCRIPTION

FIG. 1 is a perspective view of the display unit with two pockets showing my new design in an assembled state as seen from the front and left side thereof;

FIG. 2 is a front plan view thereof;

FIG. 3 is a back plan view thereof;

FIG. 4 is a left plan view thereof;

FIG. 5 is a top plan view thereof;

FIG. 6 is a bottom plan view thereof;

FIG. 7 is a perspective view as seen from the top side thereof in an unscored flat state;

FIG. 8 is a perspective view as seen from the bottom side thereof in an unscored flat state;

FIG. 9 is a perspective view as seen from the top side thereof in an unassembled state; and,

FIG. 10 is a perspective view as seen from the bottom side thereof in an unassembled state.
